UNITED STATES PATENT OFFICE

FREDERICK JACKSON ALDERSON, OF KINGSTON, ONTARIO, CANADA, ASSIGNOR OF ONE-HALF TO JOHN McARTHUR PATRICK, OF KINGSTON, ONTARIO, CANADA

INCANDESCENT LAMP

Application filed October 28, 1927, Serial No. 229,469, and in Canada October 1, 1927.

This invention relates to improvements in incandescent lamps and more particularly to electric incandescent lamps for use in automobile headlights and the objects of the invention are to overcome glare by eliminating direct radiation from the filament.

Further objects are to provide an improved incandescent lamp of this description that can be manufactured and placed on the market at substantially the same price as existing lamps of this description.

It is well known in the art that glare from automobile headlights is not only objectionable but absolutely dangerous and that many attempts have been made to eliminate it without reducing distant visibility.

In endeavoring and experimenting to provide an incandescent lamp which practically eliminates glare the causes to which glare may be justly attributed were carefully studied and they would appear to be as follows:

First—direct radiation on the lens from the filament.

Second—a deep glow at the base of the reflector which is particularly troublesome at some distance from the light on a narrow road.

Third—secondary reflection from the side walls of the reflector having the deep glow at the base as a source visible for some distance at the side.

The effect of the glare from the headlights of a car coming in the opposite direction amounts to a temporary paralysis of vision induced by the extreme localization of the approaching light, frequently resulting, even with most careful driving, in accidents serious and otherwise.

Bearing in mind the foregoing the novel features of the present invention reside in the means for eliminating direct radiation from the filament and reducing to a minimum the deep glow at the reflector base and at the same time reducing the secondary reflection from the sides.

These objects are obtained by so frosting or treating the front and rear portions of a transparent glass bulb to provide between the frosted or light diffusing sections a cir-

cumferential space or band of plain transparent glass whereby the reflected light rays of the filament are so diffused as to eliminate direct radiation and at the same time the reflection of the glow at the reflector base and 55 the secondary reflection from the sides.

Referring now to the drawing in which like characters of reference indicate corresponding parts in each figure.

Figure 1 is a view of the improved incandescent lamp.

Figure 2 is a view partly in section showing the stem supporting the filament frosted.

Figure 3 is a view of a modified form of incandescent lamp.

Referring more particularly to the drawing in which a preferred example of my invention is disclosed, A indicates the incandescent lamp as a whole particularly adapted for use with automobile headlights and 70 provided with a transparent glass bulb 10 of well known construction and shape. Centrally arranged in the bulb is the filament 11 with a filament support and a transparent supporting stem or base for the filament support 12 of any suitable material and here shown as glass.

The essential feature of my invention consists in the manner in which the bulb 10 is 80 frosted or treated to provide light diffusing zones at each end of the bulb the outer light diffusing zone extending beyond the lighting element and constituting a most important feature. As disclosed, the front portion 13 of the bulb is frosted preferably to extend beyond the filament 11 while the inner or rear end portion of the globe is also frosted or otherwise, in any suitable manner, treated as at 14, both the frosted portions 13 and 14 being spaced from one another to provide a 90 circumferential band 15 of plain transparent glass therebetween.

I am aware that incandescent lamps have already been manufactured in which the bulb is corrugated or rippled on the portion 95 opposite to the base of the lamp with a view of diffusing the rearwardly directed light rays of the filament. This in practice, however, has not proved satisfactory for the elimination of glare and I have found that by 100

frosting the rear portion of the bulb to provide a clear circumferential space or ring, as above described, between it and the frosted front portion that glare is eliminated.

5 As shown in the modified form of bulb the glass filament supporting stem 12 may also be, with advantage, frosted to register with the frosted rear portion of the bulb. Furthermore, a frosted ring 16, as shown in Figure 3, intermediate of the transparent ring 15 may also be provided.

10 As many changes could be made in the above construction and many apparently widely different embodiments of my invention, within the scope of the claim, constructed without departing from the spirit or scope thereof, it is intended that all matter contained in the accompanying specification and drawing shall be interpreted as illustrative and not in a limiting sense.

15 What I claim as my invention is:—

20 In an incandescent lamp of the character described, the combination with a forward light diffusing zone surrounding the front end of the lamp and extending midway thereof, a second restricted light diffusing zone around the base of the lamp, a light diffusing band intermediate of the aforementioned light diffusing zones and light transmitting zones between the light diffusing band and the front and base light diffusing zones and of substantially equal area, of a filament cooperative with all the aforementioned zones and terminating within the forward light 25 30 35 diffusing zone, whereby direct radiation from the filament is eliminated and the diffused light spread to illuminate the sides of a road and the like.

40 In witness whereof I have hereunto set my hand.

FREDERICK JACKSON ALDERSON.
